(57) **CLAIM**

The ornamental design for a cylinder bracket, as shown and described.

DESCRIPTION

FIG. 1 is a perspective view of the cylinder bracket; FIG. 2 is a top view of the cylinder bracket; FIG. 3 is a perspective view of the cylinder bracket; FIG. 4 is a bottom view of the cylinder bracket; FIG. 5 is left view of the cylinder bracket; FIG. 6 is a back view of the cylinder bracket; FIG. 7 is a right view of the cylinder bracket; FIG. 8 is an environmental perspective view of the cylinder bracket with a strap coupled thereto; FIG. 9 is an environmental front perspective view of the cylinder bracket with a strap coupled thereto; and, FIG. 10 is an environmental perspective view of a cylinder retained by a strap extending around the cylinder and secured to the cylinder bracket.

The mounting apertures shown in FIGS. 1, 3, 6, 8, 9, and 10, the bolts shown in FIG. 10, the strap shown in FIGS. 8, 9 and 10, and the cylinder shown in FIG. 10 are shown in dashed lines and form no part of the claimed design.

1 Claim, 6 Drawing Sheets
